Attorney.

UNITED STATES PATENT OFFICE.

WILLIAM H. CASS, OF BUFFALO, NEW YORK.

SKELETON FRAME FOR SAND-CORES.

SPECIFICATION forming part of Letters Patent No. 479,783, dated August 2, 1892.

Application filed April 6, 1892, Serial No. 428,011. (No model.)

To all whom it may concern:

Be it known that I, WILLIAM H. CASS, a citizen of the United States, residing in Buffalo, in the county of Erie and State of New York, 5 have invented certain new and useful Improvements in Skeleton Frames for Supporting a Green-Sand Core for Railroad Journal-Boxes, of which the following is a specification.

10 My invention relates to certain improvements in green-sand cores for molding and casting journal-boxes for railroad-cars, and will be fully and clearly hereinafter described and claimed, reference being had to 15 the accompanying drawings, in which—

Figure 1 is a vertical longitudinal section through a flask, cutting through the core and skeleton supporting-frame in or about line *a*, Fig. 5. Fig. 2 is a back end view of a journal-box similar to that which my invention is adapted to mold with a green-sand core. Fig. 3 is a side elevation of the skeleton supporting-frame. Fig. 4 is a side elevation of Fig. 2. It is shown for the purpose of illustrating substantially the form of journal-box 25 to be molded. Fig. 5 is a plan view of the skeleton supporting-frame.

In Fig. 1 of said drawings, 1 and 2 represent the upper and lower portions of an ordinary cast-iron flask, the parting being at the point 3. The journal-box 4 is shown in section in the sand, a rear elevation of which is also shown in Fig. 2 and a side elevation in Fig. 4.

35 The green-sand core 5 is shown in Fig. 1 in its proper position in the mold and flask. Within the core 5 is the skeleton supporting-frame. It is curved so as to conform nearly to the shape of the bottom of the journal-box, 40 as will be seen by reference to Fig. 1, and is provided with a series of upper and lower projecting pins 7, the object of which is to more securely hold the particles of sand of

which the core is composed together. These upward and downwardly projecting pins 7 45 are rigidly secured on the three longitudinal curved bars 8, (see Figs. 3 and 5,) which are fastened together by connecting-bars 9 at each end, substantially as shown in Fig. 5, the whole being preferably cast or formed in 50 one piece of cast-iron. At each end of this skeleton frame, on its undersides, is a series of two or more downwardly-projecting pieces 10, which form a portion of each end of the core and rest down upon the edges of the 55 flask at the points 11 and 12, within the openings through which the ends of the core projects, substantially as shown in Fig. 1. These end downwardly-projecting portions 10 are important because they support not only the 60 weight of the core when put in the mold, but also prevent the ends of the core from being broken by the weight of the core when set in place.

If desired, the usual vent-holes can be put 65 longitudinally through the core while being made in the ordinary and well-known way.

This skeleton frame can be used for any kind of journal-box for cars by slightly changing its form. 70

I claim as my invention—

A skeleton frame for supporting a green-sand core for molding journal-boxes for railroad-cars, consisting of a series of longitudinal bars secured together by transverse pieces 75 at the ends, each longitudinal bar being curved to conform substantially to the bottom of the core and provided with a series of upward and downward projecting pins, and downwardly-projecting supporting-pieces at 80 each end, for the purposes described.

WILLIAM H. CASS.
